UNITED STATES PATENT OFFICE.

ALBERT E. JOHNSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR OPERATING ON SOLES.

1,344,041.

Specification of Letters Patent. Patented June 22, 1920.

Application filed March 26, 1918. Serial No. 224,707.

To all whom it may concern:

Be it known that I, ALBERT E. JOHNSON, a citizen of the United States, residing at Beverly, in the county of Essex and State of Massachusetts, have invented certain new and useful Improvements in Machines for Operating on Soles; and I do hereby declare the following to be a full, clear, and exact description of the invention, such as will enable others skilled in the art to which it appertains to make and use the same.

This invention relates to machines for operating on boot and shoe soles, and more particularly to such machines for permanently setting the lip or marginal rib thereon.

The upstanding lip of certain types of insoles, in which the lip is formed by channeling or splitting the marginal portion of the sole body to form a flap, must be acted upon by some means adapted to impart a permanent bend to the lip at its base which otherwise would tend to return to its original position after it had been turned up.

This permanent setting of the lip in upstanding position is usually accomplished by machines which apply pressure to the lip and adjacent parts of the sole. Certain machines have been devised which, in addition to applying pressure to the parts, crimp or corrugate the upturned lip thereby insuring the permanence of its form. An example of a machine of this type is found in the United States patent to Albert E. Johnson, No. 1,213,770, dated January 23, 1917.

When operating on laminated material, such as leatherboard, it has been found that, whether or not the lip is crimped, the turning up of the lip tends to split the sole along the plane of cleavage of the laminae which has been divided by the channeling or splitting operation. Thus on a Gem insole, in which the lip is formed by splitting the edge of the sole and then turning up one part of the edge from the bottom of the split, the turning up of the lip tends to deepen the split in advance of the lip turning tools and as the height of the portion to be turned up is determined by the bottom of the split, the lip gradually becomes higher as its base moves inwardly toward the center of the sole. This, of course, results in a crippled insole.

One object of the present invention is to

provide a machine of the character described which will overcome the difficulty now encountered in operating on soles of laminated material. To the accomplishment of this object one feature of the invention contemplates the provision of means for positively determining the width of the marginal portion of the sole turned up to form the lip. This feature is preferably carried into effect by providing a gage for locating the edge of the sole with relation to the base of the lip being formed.

Another object of the invention is to provide a lip turning machine particularly adapted for turning up and crimping the lip of insoles made from leatherboard or an analogous nonstretchable material. To the accomplishment of this object other features of the invention reside in the form and relation of the lip engaging tools, as will be more fully described, the advantages of which will be apparent to those skilled in the art to which the invention relates.

The various features of the invention will be best understood from the following description of the preferred embodiment of the invention illustrated in the accompanying drawings, in which:

Figure 1 is a front elevation of the machine;

Fig. 2 is a detail view in perspective showing the relation of the plow for lifting the lip in advance of the crimping rolls and the presser foot for giving the upturned lip its final position;

Fig. 3 is a partial end elevation on an enlarged scale showing particularly the lip engaging tools;

Fig. 4 is a central vertical section, on an enlarged scale, of the work engaging instrumentalities;

Fig. 5 is a detail view of a portion of Fig. 4 but on an enlarged scale;

Fig. 6 is a partial section, on the line 6-6 of Fig. 5 enlarged to show the form of the inside lip crimping teeth; and

Fig. 7 is a greatly enlarged detail view of the outside lip crimping teeth.

The general construction and driving connections of the embodiment of the invention illustrated in the drawings may be and preferably is similar to that shown in the aforementioned patent. Briefly stated, the machine head 10 provides bearings for a

shaft 12 carrying the outside lip roll which is driven by a pulley 14. An inside lip roll is mounted on a shaft 16 which is carried by a movable arm 18 and driven through gears 20 from the shaft 12. The inside lip roll is pressed toward the outside roll by a spring 22. A presser roll 24 is mounted on a movable arm 26 held yieldingly toward the lip engaging rolls by a spring 28 and provided 10 with the usual treadle connections. A presser finger 30 engages the work in advance of the rolls.

The machine shown in the drawings is provided with work engaging tools constructed and arranged to operate on single lipped Gem insoles and, as is usual in a machine of this type, the inside and outside lip rolls co-act to form the upstanding lip and, in conjunction with the presser roll, to 20 feed the work. The outside lip roll, as shown particularly in Figs. 1, 3 and 4, comprises a cylindrical shank 32 screwed on to the reduced end of the shaft 12. The projecting end of the shank 32 is provided with 25 a frusto-conical flange 36 the periphery of which is provided with a series of straight teeth 38. In order that the crimp formed by the teeth 38 shall not extend to the base of the lip where it joins the feather, the 30 end of the roll is covered by a disk 40 of a diameter slightly smaller than the outside diameter of the connecting ends of the teeth 38. The disk is slotted for a screw driver and is secured to the shank 32 by a threaded 35 stem 42.

The inside lip roll comprises a cylindrical shank 44 having a tapered hole to receive the reduced end of the shaft 16. The projecting end of the shank is reduced in diameter and provided with straight teeth 48 which co-act with the teeth 38 on the outside lip roll to crimp the lip. In order that the crimp shall not extend to the base of the lip, the inside feed roll is provided with 40 a smooth edged button 50 which covers the ends of the teeth 48 and also provides a positive feeding means. As shown particularly in Figs. 4 and 5 the button 50 is driven into the shank 44 and its outer surface is provided with radial teeth 52 which engage the body of the sole about opposite the greatest diameter of the roll 24 and insure a positive feed thereof.

The means employed to limit the width 55 of the marginal portion of the sole which may be turned up to form the lip is an edge gage which is preferably arranged to engage that part of the sole edge which is being turned up to form the lip. The edge gage 54 (Figs. 1, 3 and 4) is in the form of a collar surrounding the shank 44 of the inside lip roll and engaging the edge of the lip just prior to and during the crimping 60 operation. The work engaging surface of the edge gage is in close contact with the

flange 36 of the outside lip roll in order that there may be no opening therebetween into which the edge of the lip might be forced. In order that the edge gage may not bind against the flange when the arm 18 70 is swung about its pivot to separate the rolls, it is mounted to yield against the pressure of the flange, as the edge gage is moved upwardly with the inside roll. As shown in Fig. 4, the edge gage 54 is loosely mounted 75 on the shank 44 and is forced against the flange 36 by a spring 56 surrounding the shank and confined between the edge gage and a shoulder on the shank. The edge gage is prevented from rotation with the inside lip tool by a slotted arm 58, integral with the edge gage, which embraces a bracket 60 secured to the end of the arm 18. The spring 56 is of sufficient strength to form, in effect, a rigid abutment for the lip but 85 when the rolls are separated the edge gage can yield under the action of the flange on the outside of the lip roll.

It has been found desirable to give the lip a secondary bend toward the center of 90 the sole after having been bent by the rolls. For this purpose a bending tool 62 is adjustably mounted on the bracket 60 and provided with a rounded edge 64 (Figs. 2 and 3) which engages the lip as it leaves the 95 crimping rolls and gives it a further inward bend so that when it is free to assume its final position, it will be at the desired angle to the body of the sole. This angle may be varied by adjusting the bending tool toward 100 or from the sole.

The split margin of the sole is first lifted by a plow 66 which engages the work in advance of the rolls and turns up the lip sufficiently to be engaged by the rolls. 105

The particular form of the co-acting teeth on the inside and outside lip rolls as shown in Figs. 5, 6 and 7, which is the best at present known for operating on non-stretchable sole material, has been determined by long 110 experiment on such material. The smooth edges of the button 50 and the disk 40 engage opposite sides of the base of the lip, thus determining the spacing of the teeth with respect to the lip and preventing the 115 teeth from exerting any molding pressure on the lip. The crimp therefore is formed by bending the lip as it passes between the toothed rolls as distinguished from molding a crimp by compression.

From an inspection of Figs. 4 and 5 it will be apparent that the diameter of that part of the inside lip roll in engagement with the lip is slightly tapered forming an angle sloping from front to rear. The taper 125 of the frusto-conical flange 36 is in the opposite direction forming an angle sloping from rear to front, but the two angles are not complementary, one to the other. The angles which have been found to be most 130

successful in practice, although some variation may be permitted, are an angle of $4\frac{1}{3}$ ° between the teeth 48 and the axis of the inside lip roll, an angle of 30° between the top 5 of the teeth 38 and the axis of the outside roll, and an angle of 14° between the bottom of the teeth 38 and said axis. The tops and bottoms of the teeth 38 and 48 are rounded as shown in Figs. 6 and 7, which are greatly 10 enlarged. It will be noticed that the shapes of the teeth are not generated after the manner of gear teeth, but that the tooth 48 acts to deflect the lip between the supports formed by the teeth 38 on either side.

15 It will be apparent to those skilled in the art that certain features of the invention are not limited to use in a machine for operating on the single lipped insole, which has been described, but that these features can be advantageously employed in machines for operating on other types of soles; and also certain features of the invention are of advantage when operating on soles of any material.

20 25 It will be understood that the specific construction and arrangement of the parts is not material to the broader features of the invention and may be varied and modified within the scope of the invention as defined 30 in the claims.

What is claimed as new is:

1. A machine for operating on soles having a lip on one face, having, in combination, means for turning up the lip, and additional means to determine the height of the lip.
2. A machine for operating on soles having a lip on one face having, in combination, means for turning up the lip, and means to engage the top of the lip to limit its height.
3. In a machine for turning up a lip on a sole, a gage against which the edge of the lip bears to determine the relation between the base of the lip and the edge of the sole.
4. A machine for turning up a lip on a sole having, in combination, a pair of rolls

to engage opposite sides of the lip, and a gage to limit the height of the lip engaged between the rolls.

5. A machine for turning up a lip on a sole having, in combination, a pair of rolls to engage opposite sides of the lip, a gage to limit the height of the lip engaged between the rolls, and means to permit a yielding movement of the gage longitudinally of the 55 rolls.

6. In a machine for operating on a lipped sole, a lip engaging roll having a lip engaging surface equal in width to the height of the lip, and an edge gage to prevent the lip 60 from projecting beyond the lip engaging surface of the roll.

7. A machine for operating on soles having, in combination, an outside lip roll having a lip engaging surface equal in width to 65 the height of the lip, an inside lip roll, a gage mounted thereon, and a spring to hold the work engaging surface of the gage against the back of the outside roll.

8. A machine for crimping the lip of an 70 insole having, in combination, a rotary crimping roll for engaging the outside of the lip having a series of straight teeth at an angle to the axis of the roll, and a rotary crimping roll for engaging the inside of the 75 lip having a series of straight teeth at an angle to the axis of that roll, other than complementary to the first named angle.

9. In a machine for crimping the lip of an insole, a pair of lip engaging rolls having 80 teeth constructed to engage and bend the lip therebetween into a crimp without a compression of the lip material sufficient to mold a crimp therein.

10. In a machine for crimping the lip of an insole, a pair of lip engaging rolls having teeth constructed to engage the lip therebetween and bend its free margin into a crimp leaving its base free from crimping pressure.

ALBERT E. JOHNSON.

It is hereby certified that in Letters Patent No. 1,344,041, granted June 22, 1920, upon the application of Albert E. Johnson, of Beverly, Massachusetts, for an improvement in "Machines for Operating on Soles," an error appears in the printed specification requiring correction as follows: Page 2, line 32, for the word "connecting" read *contacting*; and that the said Letters Patent should be read with this correction therein that the same may conform to the record of the case in the Patent Office.

Signed and sealed this 3d day of August, A. D., 1920.

[SEAL.]

R. F. WHITEHEAD,

Acting Commissioner of Patents.

Cl. 12—30.
